UNITED STATES PATENT OFFICE.

MILTON C. GREEN, OF KANSAS CITY, MISSOURI, ASSIGNOR TO HIMSELF AND
LEVI H. OSBORN, OF GARNETT, KANSAS.

AIR-HEATING STOVE.

SPECIFICATION forming part of Letters Patent No. 374,896, dated December 13, 1887.

Application filed March 25, 1887. Serial No. 232,382. (No model.)

To all whom it may concern:

Be it known that I, MILTON C. GREEN, of Kansas City, Jackson county, Missouri, have invented certain new and useful Improvements in Air-Heating Stoves, of which the following is a full, clear, and exact description, reference being had to the accompanying drawings, forming a part hereof.

My invention relates to an improvement in heating-stoves, and more particularly to that class of hot-air heaters in which the flame and products of combustion are passed in proximity to a chamber constantly supplied with cold air, which, as it becomes heated, is allowed to pass out into the room.

The object of my invention is to provide a cheap durable hot-air heater which shall be capable of evenly heating more space in less time and with less fuel than the heating-stoves heretofore in use; and my invention consists in certain novel features of construction and combinations of parts, as will be more fully described hereinafter, and pointed out in the claims.

In the accompanying drawings, Figure 1 represents a perspective view of my improved heating-stove and attachment, with the surrounding shells partially broken away to show the interior and the damper removed; Fig. 2, a vertical section of the same, and Figs. 3, 4, and 5 modifications.

The letter E represents a suitable base provided with legs or supports in the usual manner. The base E surrounds and supports the ash-receptacle P and the grate P', and is provided with a flange or casting, B', which is provided with a series of apertures, b, and it can be cast integral with the base E or cast separately and afterward securely fastened thereto.

B and A represent the inner and outer shells of the stove-body or fire-box, which are securely fastened at their lower ends to the flange or casting B' and at their upper ends to the top casting, A', in such a manner that a space will be left between the surfaces of the shells wide enough to admit a free circulation of air through the apertures b in the lower supporting-casting, and thence through the space between the shells and out at apertures a in the top casting, A'.

Secured to the top casting, A', by means of the flange M, and suspended within the body of the stove directly over the fire-box and beneath an opening in the top casting, is a shell, 55 C, forming a hot-air chamber, cast in the form of an inverted cone and suspended within the center of the stove-body, the upper edge thereof almost coming in contact with the inner shell of the stove.

The hot-air chamber or shell C is provided with an opening in its top, which is surrounded by the flange M, having its upper edges secured around the edges of the aperture in the top casting, A', and its lower edge around an 65 aperture in the top of the shell C, so that there will be no communication between the air in the cone-shaped shell C and the flames and products of combustion within the stove.

The hot-air shell is supplied with outside 70 cold air through the medium of the cold-air flues G G', which pass from under the ash-receptacle and the base E up through the fire-box and thence diagonally across to the lower extremity of the hot-air chamber. These cold-air flues as they enter the fire-box gradually increase in diameter as they approach the hot-air chamber, thereby causing the air to flow swiftly and freely into the hot air shell by allowing for its expansion as it becomes more 75 80 and more heated.

Located in and extending through the center of the hot-air shell C is a fuel-magazine, D, the lower part of which passes through the apex of the cone-shaped shell and opens into 85 the fire-box, and its upper end passes through the opening in the top of the air-shell and extends through the aperture in the top casting. As the sides of the magazine pass through the opening in the top casting they are made to 90 diverge, thus increasing the diameter of the top or mouth thereof, so that when the magazine is being filled the fuel will not fall over the edge into the hot-air chamber.

The fuel-magazine is provided with an outer 95 shell, D', which is secured so that an air-space will be formed between the hot air in the shell C and the fuel in the magazine, thus keeping the fuel from becoming heated and ignited within the magazine.

The magazine is provided with a suitable cover, 6, adapted to fit tightly over the top

thereof and prevent the products of combustion from escaping into the room. A damper, H, is located in the top of the fire-box surrounding the flange M, whereby the heat of 5 the fire can be regulated.

The products of combustion are allowed to pass out through a suitable pipe, F, in communication with the interior of the fire-box and the outer air.

10 It will be readily seen that when a fire is kindled in the fire-box the flame and heated products of combustion, passing up, around, and over the cone-shaped air-shell, will heat the air within said shell, causing it to expand and pass out through the apertures in the top casting, A', which causes cold air to constantly flow in through the funnel shaped cold-air flues to prevent a vacuum being formed within the air-shell, thereby keeping up a 15 steady circulation of air from the floor up through the stove, where it becomes heated, out into the room again. This steady current of cold air through the flues G G' also keeps them from "burning out," which would otherwise soon be the case, owing to their close 20 proximity to the intense heat of the fire. As the flames and heated products of combustion flow up the sides of the conical shell C, they are deflected against the inner shell of the fire- 25 box by reason of the sloping sides of the inverted cone, thus doubly heating the air within the space B² between the two shells and causing it to rise and flow upward out into the room while the space is supplied with cold air 30 through the apertures in the lower supporting- 35 casting.

The radiated heat from the sides of the stove would be intense and unpleasant, as the sides of the cone deflect the heat so strongly against 40 the inner shell, were it not for the fact that the outer shell is provided, and consequently the air-space is formed, to obviate this great disadvantage, thus allowing the heated air to pass up and out at the apertures a, instead 45 of being radiated directly out from the sides of the stove.

It is evident that my hot-air shell, having the downwardly-converging sides provided with cold-air flues and having its top in communication with the outer air, can be used in 50 many different styles and forms of stoves and heating-drums. For example, Fig. 3 shows the hot-air shell and flues applied to a heating-drum in which the magazine is dispensed

with and the heated air is allowed to flow out 55 through the flues C C" while cold air is supplied through the flues G G', the flame and heated products of combustion passing directly from the fire-box through the opening L' into the drum.

60 It is also evident that many changes can be made in the form of the hot-air shell, as illustrated by Figs. 4 and 5, which are a perspective and sectional view of a horizontal stove adapted to burn wood, in which are located 65 two or more hot-air shells provided with the downwardly-converging sides, said shells being communicating and adapted to rest one on the other, the cold air being supplied through flues G G' G² G³, while the air as it 70 becomes heated passes through the bottom of the lower shell into the upper one and out into the open air through the slot L in the top of the stove and uppermost hot-air shell.

Having thus fully described my invention, 75 what I claim as new, and desire to secure by Letters Patent, is—

1. In a heating-stove, the combination of the usual shell, B, the conical hot-air shell C, suspended within said shell B directly over the fire-pot and having its upper portion in communication with the outer air, and cold-air flues extending from the open air beneath the stove into the lower portion of said cone-shaped shell, the diameter of said flues gradually increasing as they approach the hot-air shell, substantially as described.

2. In a heating-stove, the combination of the outer shells, A B, a conical hot-air shell suspended within said shells directly over the fire-pot and having an opening in its top portion, a flange, M, secured to said hot-air shell and surrounding said opening therein, and also being secured to the top A', and cold-air flues having one end open to the air beneath 95 the stove and the opposite ends passing upwardly through the fire-box and opening into the lower portion of said hot-air shell, the diameter of said flues gradually increasing as they approach said cone-shaped shell, substantially as described.

In testimony whereof I affix my signature in presence of two witnesses.

MILTON C. GREEN.
